US00D671892S

(12) **United States Design Patent**
Keith, Jr. et al.(10) **Patent No.:** US D671,892 S
(45) **Date of Patent:** ** Dec. 4, 2012(54) **PORTION OF A POWER BASE**(75) Inventors: **James A. Keith, Jr.**, Pickens, SC (US);
Michael E. Buckner, Clemson, SC
(US); **Ronald C. McCurry**, West Union,
SC (US)(73) Assignee: **Techtronic Power Tools Technology
Limited**, Tortola (VG)(**) Term: **14 Years**(21) Appl. No.: **29/389,759**(22) Filed: **Apr. 15, 2011**(51) **LOC (9) Cl.** ..... 13-03(52) **U.S. Cl.** ..... D13/133(58) **Field of Classification Search** D13/133,
D13/146, 147, 154, 184, 199, 439/180, 246,
439/252, 259, 278, 296, 350, 352, 353, 354,

Primary Examiner — Daniel Bui(74) *Attorney, Agent, or Firm* — Michael Best & Friedrich
LLP(57) **CLAIM**We claim the ornamental design for a portion of a power base,
as shown and described.**DESCRIPTION**FIG. 1 is a perspective view of a portion of a power base
showing our new design;

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The portions of the power base shown in broken lines are
included for the purpose of illustrating environment and form
no part of the claimed design.**1 Claim, 4 Drawing Sheets**## U.S. PATENT DOCUMENTS
